UNITED STATES PATENT OFFICE.

CHARLES E. DURYEA, OF READING, PENNSYLVANIA.

INTERNAL-COMBUSTION ENGINE.

949,758.

Specification of Letters Patent. Patented Feb. 22, 1910.

Original application filed June 7, 1902, Serial No. 110,598. Divided and this application filed April 8, 1907. Serial No. 367,082.

To all whom it may concern:

Be it known that I, CHARLES E. DURYEA, citizen of the United States, residing at Reading, in the county of Berks and State 5 of Pennsylvania, have invented certain new and useful Improvements in Internal-Combustion Engines; and I do hereby declare the following to be a full, clear, and exact description of the invention, such as will 10 enable others skilled in the art to which it appertains to make and use the same.

My invention relates to that class of engines in which the piston uncovers an exhaust port and permits a quantity of air and 15 explosive mixture to be introduced before the return of the piston closes the exhaust port.

The objects of my invention are to utilize 20 the energy of the exhaust gases to insure induction of pure air or mixture or both with little reference to the speed of the engine, or length of the exhaust pipe l' , or 25 similar modifying features, and to provide an engine of great simplicity, great reliability and great economy with minor improvements. The means by which I accomplish 30 these results was shown in my application Serial Number 110,598 of which this is a division, and consists of the mechanism illustrated in the accompanying drawings, of which—

Figure 1 is a sectional elevation of an engine to which my device is applied. Fig. 2 is a section of the fan chamber and Fig. 3 35 is a plan view of the fan.

Similar letters refer to similar parts throughout the several views.

The engine shown in Fig. 1 is constructed 40 with fly wheel, crank shaft, piston and bearings in the most common manner with cylinder head downward and with an exhaust port uncovered by the piston when near the upper end of its stroke. The cylinder head is provided with an air inlet g and a fuel 45 supply arrangement consisting as shown of pump d and operating means. While I have shown an air inlet g , I can with equally good results provide an air port opposite the exhaust port b but of less length than the 50 exhaust port b as is customary in two cycle engines. I may also provide an inwardly opening valve and a pipe to a carburetor or fuel mixing device instead of the pump d , with valves and operating mechanism as 55 shown. In short the construction of the

engine is not of great import so far as the operation of the invention described herein is concerned.

From the exhaust port b a pipe leads to a fan chamber l^2 and in this chamber is 60 located an exhaust fan l of any preferred construction which is mounted in bearings so that the impingement of the exhaust gases on the under side of the fan l causes it to revolve rapidly and having considerable momentum, it will continue to revolve after the flow of exhaust gases has ceased. This continued revolution serves to exhaust the lower 65 part of the fan chamber l^2 , the exhaust pipe leading thereto, and so long as the exhaust port d is open, it will continue to form a partial vacuum within the cylinder and thus cause either air to flow in through the air inlet g or through the fuel inlet valve of the fuel supply apparatus d .

I have demonstrated by repeated usage 75 that with certain speeds of an engine, and proper sized inlet valves or ports and an exhaust pipe of proper size and length, the flow of air for scavenging, and the flow of 80 fuel or mixture for the succeeding explosion is all that could be desired, but for wide variation of speeds the continued vacuum given by the use of the exhaust fan l is of great value. The reason for this is plainly 85 due to the fact that the exhaust gases act with great energy and swiftness, and unless the speed of the motor is such that the desired incoming air and mixture is permitted to enter, the vacuum produced by the exhaust 90 gases may cease to exist and leave the cylinder not properly charged for the next explosion. The exhaust fan l because of its weight and great inertia never acquires a speed equivalent to the maximum 95 speed of the exhaust gases but it maintains a rate of revolution sufficient to produce the working vacuum and this vacuum is always ready to act whenever the exhaust port is open, because the exhaust fan l continues 100 its motion with little diminution between the explosions. If for any reason, such as seizing of bearings, this exhaust fan becomes inoperative, it does not greatly impede the escape of the exhaust gases and therefore 105 permits the engine to continue operation through the medium of the vacuum produced by the momentum of the outgoing gases as described in my original specification 110,598. While I have shown 110

this exhaust fan 7 mounted on a case or bracket in the chamber or exhaust pipe enlargement 7² I may construct it in a variety of ways, and particularly in a manner to 5 terminate the axis of shaft of the fan 7 in the walls of the chamber 7² where the bearings may be provided with lubrication and may be kept cool by contact with the air surrounding the chamber. I may use 10 other means of cooling the bearings without departing from the spirit of this invention; or other shape of fans, so long as they perform the functions necessary and are not likely to impede seriously the escape of the 15 exhaust gases. I can make the piston length shorter than the engine stroke so that when the piston is near the head of the cylinder, the exhaust port will be uncovered and a flow of cool air pass from the open end of 20 the cylinder, out through the exhaust pipe, effectually cooling the fan. It is well known however, that the rapid expansion of exhaust gases cools them greatly and that lubricants such as graphite are not affected 25 by heat, so the construction shown is a thoroughly practical one.

I claim,

1. The combination with the exhaust pipe 30 of an engine, of a fan chamber intermediate the length of said pipe and a fan mounted in said chamber near the midheight thereof

with the blades arranged at right angles to the length of the pipe so that the impingement of the exhaust gases on the under side thereof will cause it to revolve rapidly and 35 to exhaust the lower part of the fan chamber and the exhaust pipe leading thereto and form a partial vacuum within the cylinder.

2. The combination with the exhaust pipe 40 of an engine, of a fan chamber intermediate the ends of said pipe and of greater diameter than the pipe and an induction device in said chamber and comprising a fan disposed substantially at the midheight of said chamber and adapted to be revolved by direct impact of the exhaust gases, the inlet and outlet to said chamber being in substantially direct straight lines through the transverse axis of the chamber, whereby said fan will 45 keep the path of the exhaust gases practically straight before and after they reach the fan and the fan will continue to act as an inductor and create a vacuum in the cylinder after the flow of exhaust gases has 50 ceased.

In testimony whereof I affix my signature, in presence of two witnesses.

CHARLES E. DURYEA.
